UNITED STATES PATENT OFFICE.

WILLIAM W. KEEFER, OF PITTSBURG, AND CHARLES E. WARD, OF BANKSVILLE,
PENNSYLVANIA.

LUBRICATOR.

No. 864,002.

Specification of Letters Patent.

Patented Aug. 20, 1907.

Application filed April 22, 1907. Serial No. 369,450.

To all whom it may concern:

Be it known that we, WILLIAM W. KEEFER and CHARLES E. WARD, residents of Pittsburg and Banks-ville, in the county of Allegheny and State of Penn-sylvania, have invented certain new and useful Im-5
provements in Lubricators, of which the following is a specification.

This invention relates to the lubrication of car axles and other rotating shafts or journals, and it is designed 10 with special reference to the requirements of mine cars having axles which rotate in bearings secured to the car.

It is a common practice to locate an oil box or reser-15 voir beneath a journal and to convey the lubricant up-wardly thereto, usually by a ring depending from the journal into the oil. The oil is held within the recep-tacle so long as the latter remains upright, but when the car is tilted, and in fact turned completely upside down, as is often the case when emptying its contents, 20 the journal is flooded and much of the oil wasted.

The primary object of this invention is to so con-struct the oil receptacle as to confine the oil regardless 25 of the position in which the car and the oil receptacle may be placed.

25 The invention is an improvement in the oil receptacle shown in Letters Patent granted us June 5, 1906, No. 822,671, relating to mine cars, and while designed primarily for use in this connection, it is obviously not restricted thereto.

30 In the accompanying drawings, Figure 1 is a side ele-vation of a mine car, partly in section, showing our im-provement applied thereto, and Fig. 2 is a similar end view. Fig. 3 is a vertical sectional view of one of the 35 bearings and the oil receptacle, taken on line 3—3 of Fig. 4. Fig. 4 is a sectional view taken on line 4—4 of Fig. 5, and Fig. 5 is a similar view, inverted, taken on line 5—5 of Fig. 4.

Referring to the drawings, 2 designates the body of the car, and 3 the bearings secured to the under side 40 thereof in which axles 4 are adapted to rotate.

5 are the wheels. As shown in our above mentioned patent, the bearings on each side of the car are prefer-ably formed integral with a sill member 6 extending longitudinally of the car; this, however, being only in-45 cidental to the present improvement.

Each of the bearings consists of an integral box-like structure, and formed longitudinally therethrough is the circular axle or journal passage 7, which constitutes

the immediate bearing, while the lower portion 8 of the structure forms the oil-confining receptacle. Bearing 50 7 is divided by the ring slot or passage 9 formed down-wardly therethrough and open at the top for the inser-tion and removal of the lubricating ring 10, which hangs loosely therein upon the journal and depends into the oil chamber. Coincident with the ring slot 9 are the 55 two parallel walls or partitions 11, reaching nearly to the bottom of the oil chamber, thus dividing the latter into two compartments 12 and 12' which freely com-municate beneath partitions 11, where they are also open to the ring space 9, thus affording the oil free cir-culation in the chamber and around the depending 60 part of the ring. The oil may be inserted through an oil passage 13 extending inwardly through the axle or journal and branched at its inner end at 13' to intersect ring slot 9. With the oil chamber thus construct-65 ed, the car may be tilted either on its side, or its end, or it may be turned completely upside down without wasting the oil, the latter being held within either compartment 12 or 12', or in both, when the car and bearing are in any of the abnormal positions mentioned. 70

We claim:—

1. A journal bearing having a depending oil chamber wholly closed excepting for a vertical ring passage open through the bearing surface, and means for preventing oil from escaping from the chamber through said passage 75 when the bearing is inverted.

2. A journal bearing having a depending oil chamber closed excepting for a ring passage open through the bearing surface, the chamber having a compartment be-neath said passage which is open only at its lower end 80 to the remainder of the chamber.

3. A journal bearing having a depending oil chamber closed at the top or beneath the bearing surface excepting for a ring passage, and walls at opposite sides of the pas-sage, said walls extending downward from the top of the 85 chamber and reaching to opposite sides thereof with the spaces at opposite sides of the walls communicating only at the lower ends of the latter.

4. A journal bearing having a depending oil chamber closed at its ends and at its top excepting for a ring pas-sage through the latter, and upright transverse walls 90 within the chamber at opposite sides of the passage and terminating above the chamber bottom.

In testimony whereof we affix our signatures in presence of two witnesses.

WILLIAM W. KEEFER.
CHARLES E. WARD.
